UNITED STATES PATENT OFFICE.

CARL PAULI, OF ROSELLE PARK, NEW JERSEY, ASSIGNOR TO GARWOOD COMPANY, OF GARWOOD, NEW JERSEY, A CORPORATION OF NEW JERSEY.

MECHANICAL MOVEMENT.

1,215,056.

Specification of Letters Patent. Patented Feb. 6, 1917.

Application filed September 17, 1915. Serial No. 51,187.

To all whom it may concern:

Be it known that I, CARL PAULI, a citizen of the United States, residing in Roselle Park, in the county of Union and State of New Jersey, have invented certain new and useful Improvements in Mechanical Movements, of which the following is a specification.

My present invention relates to an improved mechanical movement, which movement finds particular utility as a hammer for impact drills adapted for dental work, stone cutting, and the like.

One of the important objects of the present invention is to provide in a rotary tool of the above-noted type, as few a number of parts in the operative element as possible and to construct a tool that may be operated at an extremely high rate of speed by which the cumulative force delivered in a given period of time is greatly increased thereby adding to the efficiency of the tool to which this movement is applied.

A further object in the present movement is to provide means structurally incorporated into the movement whereby the wear between the tool-holding shank or anvil and the impact member is evenly distributed.

A particular feature of the invention is the provision of a loosely mounted impact member maintained in striking position by centrifugal force and mounted sufficiently loose to permit its rebounding or yielding upon engagement with the anvil or other element cooperating therewith.

Another feature of the invention is the provision of an eccentric for guiding the ring.

Features of one embodiment of the invention are the provision of one or two disks on or between which an eccentric is fixed on which the ring or annular hammer is loosely mounted, the disks serving as lateral guides for such hammer; and the provision, in a combination having such disks between which an eccentric is fixed on which the annular hammer is mounted, of the formation, or rather deformation, of such disks so that they counterweight for the eccentric.

In the accompanying drawings, my device is shown in one of its forms of utility as a stone drill, although it is obvious that

it may be adapted to any other requirement to which mechanical impact hammers are applied.

These and other features, capabilities and advantages of the present improvement will more fully appear from the subjoined detail description of one specific embodiment thereof, in which—

Fig. 1 is an elevation, partly in section, illustrating one embodiment of the present invention in a complete working apparatus.

Fig. 2 is an end elevation of the same with the end covering disk removed.

Fig. 3 is a fragmental side elevation illustrating the position of the hammer when in contact with the drill holder.

Fig. 4 is an elevation, parts being removed, illustrating the position of the hammer when engaging the drill holder.

Fig. 5 is an elevation similar to Fig. 4 showing the position of the hammer in a position most remote from the drill holder.

Fig. 6 is an enlarged detail view showing the hammer and its mounting, the hammer being in engagement with the drill holder.

Fig. 7 is a fragmental end elevation of the parts shown in Fig. 6.

Figs. 8, 9 and 10 are fragmental elevational views, partly in section, illustrating three successive positions of the hammer when in the course of operation.

Fig. 11 is a side elevation of another embodiment of the present invention in which but one disk member is used, and in which a spring is added to assist the centrifugal force in maintaining the hammer in its outward position.

Fig. 12 is an end elevation of the embodiment shown in Fig. 11 with the hammer in contact with the anvil or tool-holding shank; and Fig. 13 is a similar side elevation showing the hammer in a position remote from the anvil or tool-holding shank.

Fig. 14 is a side elevation of the hammer detached.

Fig. 15 is a side elevation of still another embodiment of the invention in which the hammer or impact member is anchored in a rotatable housing.

Fig. 16 is an end elevation, partly in section, of the embodiment illustrated in Fig. 15.

Fig. 17 is a perspective of the housing of the embodiment shown in Fig. 15.

In the embodiment shown in Figs. 1 to 10 inclusive, the mechanical movement forming the basis of the present invention, is shown used with a device such as a motor-driven rock drill, in which there is provided a casing C having a large housing portion 12 for guiding a motor M, a small housing portion 13 for guiding the hammer R and the thereto related parts, and a neck portion 14 affording communication between the housing portions 12 and 13 through which pass the connection from the motor M to the operating means of the hammer R.

The enlarged housing portion 12 is provided, at its free end, the rear end of the apparatus, with a handle 15, and on its upper face with a handle 16 by means of which 20 handles the apparatus is grasped and manipulated while being operated.

The motor M is resiliently mounted, it being attached by means of springs such as the pairs of springs 17 and 18 with the 25 inner wall of the housing portion 12. The rear wall of the housing 12 is provided with an opening 19 through which passes the feed cable 20 for the motor M.

The small housing portion 13 is provided 30 with a rear wall 21 dividing the housing 13 from the neck portion 14, which wall 21 extends inwardly of the outer wall of the neck portion 14. Such wall 21 is provided with a centrally disposed opening around 35 which is formed a hub 22 to form a bearing for the collar 23 in which one end of the shaft 24 of the hammer is disposed. The other end of the shaft 24 is disposed in the collar 25 fixed in the hub 26 centrally disposed of the disk 27 which is secured to the front edges of the outer wall member of the small housing 13. The rear end of the shaft 24 is provided with a coupling member 28 having two fingers 29 spaced from one another on opposite sides of the center of such coupling member, which fingers 29 are adapted and when in proper position disposed to engage the fingers 30 of the coupling member 31 fixed to the shaft of the motor M, the 45 fingers 30 of the coupling 31 likewise being disposed on opposite sides of the center of such coupling member 31. By the aforesaid coupling members 28 and 31, a flexible connection is provided between the shaft 24 and 50 the motor M, and thus the shocks, due to the engagement of the hammer R with the tool holder T, be largely absorbed, and on the return to the motor M, the resilient mounting of the motor M further absorbing 55 such injurious shocks.

The lower end of the housing 13 is provided with a downwardly extending portion 32, the lower end of which is formed into a hub 33 through which extends the tool-receiving end 34 of the tool holder T, such

tool holder T having a shoulder 35 above the tool-receiving end 34 by means of which it is anchored in place in said hub 33. Above the shoulder 35 extends the hammer-engaging portion 36 of the tool holder T. The 70 disk 27 secured to the front edges of the outer wall of the housing 13 has a downwardly extending portion 37 to engage the front edges of the downwardly extending portion 32 of the housing 13, such portion 75 37 extending to and engaging the hub 33.

On the shaft 24 is secured the hammer-guiding member E. In the present instance, the hammer-guiding member comprises an eccentric mounted on the shaft 24 and fixed 80 to rotate with the same. Preferably, though not necessarily, disks D are provided to which, in the present instance, the hammer-guiding member E is secured, the disks forming lateral guiding or confining members for the hammer R and being keyed to the shaft 24 or in any other suitable way fixed to rotate with the shaft 24. The disks D, as shown in Figs. 8, 9 and 10, are constructed to counterweight for the eccentric E, in the present instance, each disk being provided with a number of holes 38 in one half thereof to diminish the weight of such half an amount sufficient so that the weight of such eccentric E will be counterbalanced by said disks D and permit the even rotation of such shaft 24 and the disks D and eccentric E.

The hammer R comprises essentially an annular member or ring, (Fig. 14) of any 100 suitable width and thickness, in the present instance, however, preferably being of a width slightly less than the width of the eccentric E so that the hammer R will have a good working fit between the disks D. The size of the opening of the hammer R is essentially such that the hammer R may project beyond the peripheries of the disks D when engaging the face *a* of the eccentric E, and on the other hand be wholly confined within the peripheries of the disks D when engaging the face *b* of such eccentric E. The disks D preferably have the width smaller than the width of the hammer R.

The operation of the device shown in Figs. 1 to 10 is as follows: When the shaft 24 is rotated the hammer R will gradually, by means of centrifugal force, work its way to the face *a* of the eccentric E where it will project beyond the peripheries of the disks D, the apparatus having previously been set into engagement with the work to be operated upon, the whole apparatus will rest on the tool held in the tool holder T, in which position the tool holder T, as shown in Fig. 1, will be maintained normally in the path of movement of the projecting portion of the hammer R, in which position the hammer R will strike the tool-holder T and rebound away from the face 110 115 120 125 130

a of the eccentric *E*. Upon the continued rotation of the shaft 24, due to centrifugal force, the hammer *R* will again assume its outwardly projecting position in which it engages the face *a* of the eccentric *E*.

- By means of the foregoing arrangement, it is made possible that the wear on the hammer *R* will be evenly distributed throughout its entire peripheral surface.
- 10 This is accomplished in that, whenever the hammer *R* engages the tool-holder *T*, due to friction, it will be retarded slightly relative to the rotation of the shaft 24, and upon the next engagement of the face *a* by 15 the hammer *R*, the hammer *R* will have changed its position and thus the engaging portion of the hammer *R* will be continually changing and gradually walk entirely around the peripheral surface thereof.
- 20 In the embodiment shown in Figs. 11 to 13 inclusive, there is provided a housing 40 comprising a disk member 41 and a crescent-shaped member 42 integral therewith on one side thereof. The housing 40 is fixed 25 on the shaft 43 to rotate therewith. On the shaft 43 is loosely mounted a hammer 44 substantially identical with the hammer *R* shown in Fig. 15, which is used in the embodiment shown in Figs. 1 to 10. The outer 30 periphery of the hammer 44, as is shown, is preferably such that even in its most retracted position, its center of gravity will be eccentric to the shaft 43 and nearer the open side of the crescent-shaped member 42 35 than the closed side of the same.

For assisting the centrifugal force in maintaining the hammer 44 in its outer anvil-engaging position, a flat spring 45 is provided which is secured in a recess 46 formed in the trough of the crescent-shaped member 42. In Figs. 11 and 12, the hammer 44 is shown in engagement with a tool-holding shank 57, while in Fig. 13, the tool-holding shank 57 is in engagement with the 45 crescent-shaped member 42.

The operation of the present embodiment is substantially the same as that of the embodiment illustrated in Figs. 1 to 10, therefore reference may be had to the explanation 50 of the operation of the embodiment shown in Figs. 1 to 10.

In the embodiment shown in Figs. 15 to 17 inclusive, there is provided a housing 48 comprising a disk member 49 and a crescent-shaped member 50. This housing 48 is mounted to rotate with a shaft 51, which is preferably integral with the housing 48 and extends from the disk member 49. The shaft 50 is formed so that the opening between its two parallel edges 52 is considerably narrower than the greatest width of the chamber 53 formed by the crescent-shaped member 50. This formation is such that when the hammer or impact member 54 65 is positioned in said chamber 53, it may be

free to rebound and yet be anchored in said chamber and against discharge therefrom through such opening formed between the edges 52. The hammer or impact member 54 in the present embodiment comprises essentially a cylindrical member of a diameter greater than the distance between the edges 52, and less than the diameter of the chamber 53, so that the same cannot be discharged between the edges 52 and yet be free to rebound in said chamber 53. For securing the hammer 54 against lateral displacement, a disk member 55 is secured to the lateral side 56 of the crescent-shaped member 50. The disk-shaped member 49 of the housing 48, and the disk-shaped member 55, preferably have a straight side 57 at the side between the edges 52, both for appearance and to counterweight for the increase of weight on that side due to the overhanging 85 or outwardly extending portion of the hammer 54.

In Figs. 15 and 16, the hammer 54 is shown in engagement with the tool-holding shank 58. The operation of this embodiment is also similar to the embodiment illustrated in Figs. 1 to 10, and therefore it will suffice to refer to the explanation of the operation of the latter embodiment.

It is obvious that various changes and 95 modifications may be made to the details of construction without in any way departing from the spirit or scope of this invention.

I claim:

1. In a mechanical movement, a rotatable 100 shaft, an anchoring member encircling said shaft and mounted on said shaft, and an annular hammer encircling said shaft and anchored by said anchoring member to be actuated by the rotation of said shaft thereby 105 to be swung into a position where its center of gravity is remote from the center of gravity of said shaft, said floating member being in the form of a ring.

2. In a mechanical movement, a rotatable 110 shaft, an eccentric guiding member mounted to rotate with said shaft, and an annular hammer through which said shaft extends and guided by said eccentric and adapted to be actuated by the rotation of said shaft to be swung into a position where its center of gravity is remote from the center of gravity of said shaft.

3. In a mechanical movement, a rotatable 120 shaft, an eccentric mounted to rotate with said shaft, and an annular hammer through which said shaft extends and guided by said eccentric and adapted to be actuated by the rotation of said shaft to swing into a position where its center of gravity is remote 125 from the center of gravity of said shaft.

4. In a mechanical movement, an annular hammer, a shaft extending through said hammer, and means for locating said hammer eccentric to said shaft so that when said 130

- shaft is rotated said hammer will be thrust into a position where its center of gravity is remote from the center of gravity of said shaft.
5. In a mechanical movement, an annular hammer, a shaft extending through said hammer means for locating said hammer in a position eccentric to said shaft, said hammer having considerable play for movement relative to said shaft, and means for normally maintaining said hammer in a position where its center of gravity is remote from the center of gravity of said shaft.
6. In a mechanical movement, a floating member, a shaft extending through said floating member, means for locating said floating member in a position eccentric to said shaft, said floating member having considerable play for movement relative to said shaft, and means for positively rotating said shaft thereby to actuate said floating member into a position where its center of gravity is remote from the center of gravity of said shaft.
15. 7. A percussion tool having a rotatable shaft, an eccentric on said shaft, an annular hammer loosely mounted on said eccentric, and means for rotating said shaft thereby to actuate said hammer into a position where its center of gravity is remote from the center of gravity of said shaft.
20. 8. In a percussion tool, the combination with a rotatable shaft, of an annular hammer, a tool-holder normally extending into the path of movement of said hammer when actuated, means on said shaft for loosely mounting said hammer, said hammer encircling said shaft, said means permitting the rebounding of said hammer when it engages the tool-holder in the act of striking the same and means for rotating said shaft.
25. 9. In a percussion tool, the combination with a rotatable shaft, of an annular hammer, a tool-holder normally extending into the path of movement of said hammer when actuated, an eccentric on said shaft for loosely mounting said hammer, said eccentric confining said hammer between a position slightly eccentric to said shaft to permit the ready outward thrust of said hammer into engagement with said tool holder when said shaft is rotated, and an extreme eccentric position where the tool holder will be disposed in the path of movement of said hammer, said eccentric permitting the rebounding of said hammer when it engages the tool-holder in the act of striking the same and means for rotating said shaft.
30. 10. In a percussion tool, the combination with a shaft, of a tool holder normally extending into the path of movement of said hammer when actuated, an eccentric fixed on said shaft, an annular hammer loosely mounted on and encircling said eccentric, the inner face of said hammer being cir-
35. 11. In a percussion tool, the combination with a casing having a large housing, a small housing, and a neck portion connecting said housings, a motor disposed in said large housing, a hammer disposed in said small housing, a shaft in said small housing on which said hammer is mounted, a connection connecting said motor with said hammer extending through said neck portion, said neck comprising a coupling member on said shaft provided with outwardly extending fingers, and a coupling member on said motor provided with outwardly extending fingers adapted to engage the outwardly extending fingers of said shaft thereby to provide a yieldable connection between said motor and said shaft.
40. 12. In a percussion tool, the combination with a casing having a large housing, a small housing, and a neck portion connecting said housings, a motor disposed in said large housing, resilient means for mounting said motor in said large housing, a hammer disposed in said small housing, a shaft in said small housing on which said hammer is mounted, a connection connecting said motor with said hammer and extending through said neck portion, said connection comprising a coupling member on said shaft provided with outwardly extending fingers, and a coupling member on said motor provided with outwardly extending fingers adapted to engage the outwardly extending fingers of said shaft, said coupling members and resilient mounting means of said motor absorbing the shocks occasioned by the operation of said hammer and preventing the return of such shocks to said motor.
45. 13. In a percussion tool, the combination with a shaft, of an annular hammer, a tool-holder normally extending into the path of movement of said hammer when actuated, an eccentric on said shaft for loosely mounting said hammer, and a disk on both sides of said hammer laterally guiding the same.
50. 14. In a percussion tool, the combination with a shaft, of an annular hammer, a tool-holder normally extending into the path of movement of said hammer when actuated, disks spaced from one another and mounted on said shaft, and an eccentric secured between said disks on which said hammer is loosely mounted, the disks serving to laterally guide said hammer.
55. 15. In a percussion tool, the combination with a rotatable shaft, of an annular hammer, a tool-holder normally extending into the path of movement of said hammer when actuated, eccentric supporting means on said shaft, and an eccentric secured to said supporting means, the annular hammer encir-

eling said eccentric, said eccentric permitting the rebounding of said hammer when it engages the tool-holder in the act of striking the same.

- 5 16. In a percussion tool, the combination with a shaft, of an annular hammer, a tool-holder, disks spaced from one another and fixed on said shaft, a seat secured between said disks on which said hammer is loosely 10 mounted, the disks being of smaller diameter than said annular hammer, said annular hammer projecting beyond the peripheries of said disks when rotated, and the tool-holder normally extending into the path of 15 movement of said hammer when so projecting beyond the peripheries of said disks to be engaged thereby.
17. In a percussion tool, the combination

with a rotatable shaft, of an annular hammer, a tool-holder, eccentric supporting 20 means fixed on said shaft, an eccentric secured to said supporting means, the hammer encircling said eccentric, said annular hammer projecting into tool holder striking position when rotated, and the tool-holder 25 normally extending into the path of movement of said hammer when so projecting into tool holder striking position, the eccentric permitting the rebounding of said hammer when it engages the tool-holder in the 30 act of striking the same.

CARL PAULI.
